UNITED STATES PATENT OFFICE.

JAMES G. BLUNT, OF SCHENECTADY, NEW YORK.

LOCOMOTIVE-DRIVING-BOX CELLAR.

Application filed May 14, 1926. Serial No. 109,059.

My invention relates to lubricant cellars of locomotive driving boxes, and its object is to provide a cellar of simple, substantial, and inexpensive construction, which will be 5 easily insertible in, and removable from, a driving box of ordinary type; which will, by its capacity of being readily and quickly opened, without disturbance of its connections to the driving box, facilitate its replenishment with lubricant, as from time to time required, with an economy of time, and avoidance of liability to loss of parts; and which will remain securely closed while lubricant is being supplied to the journal.

15 The improvement claimed is hereinafter fully set forth.

In the accompanying drawing: Figure 1 is a view, in perspective, of a locomotive frame pedestal and driving box, with a lubricant cellar embodying my invention, shown open for replenishment of lubricant; and, Fig. 2, a vertical longitudinal section through the cellar, in closed position.

In the practice of my invention, referring 25 descriptively to the specific embodiment thereof which is herein exemplified as applied in connection with a driving axle box, 2, of the ordinary construction, fitted in pedestal jaws, 1^a, of a locomotive frame, 1, I 30 provide a lubricant cellar, indicated, as a unitary member, by the reference numeral, 4, which is adapted to fit between the legs of the box, 2, and is of rectangular section, the body of said cellar comprising a bottom plate, 4^a, vertical side walls, 4^b, and a vertical back end wall, 4^c, said side and back end walls being integral with the bottom plate. The outer end of the body is closed by a front end wall, 4^d, which is detachably connected to the side walls, 4^b, of the body. Hinge pivot lugs, 4^e, having inclined outer faces, 4^f, and horizontal bottom faces, 4^g, are formed on the bottom plate, 4^a.

The front end wall, 4^d, of the lubricant 45 cellar, is hinged to the body thereof, and forms a lid for the cellar, which enables it to be replenished or repacked with lubricant, as may, from time to time, be required, without detaching or removing it from the driving box, 2. The lid, 4^d, is hinged to the pivot lugs, 4^e, at the front of the bottom wall of the cellar, by a pivot pin, 5, and held in open and closed positions by two plate springs, 6. Each spring has an intermediate portion, which bears on the inner side

of the lid; a straight bottom portion, which extends through a recess at the bottom of the lid, and bears upon one of the cam faces, 4^f, of one of the hinge lugs; and a top portion, disposed at substantially a right angle to the bottom portion, and extending through a slot, which is disposed above the recess, and extends from the inner to the outer side of the lid. The top portion of each spring terminates in an upwardly extending flange, or 60 lug, which bears on the outer side of the lid, above the slot. It will be seen that the described construction obviates the use of rivets to hold the spring in place.

Perforated lugs, 4^h, are formed on the 70 sides of the lid, at its top, to serve as grips for facilitating its opening and closing, and lugs, 4ⁱ, are also formed in it, below the lugs, 4^h. A locking pin, 7, is passed through perforations in the lugs, 4^h, of the lid, and 75 in lugs, 4ⁱ, on the side walls of the cellar, which align with the lugs, 4^h, to prevent possibility of accidental opening of the lid, due to lack of sufficient tension in the spring, 6.

The lubricant cellar of my invention 80 which is herein set forth is differentiated from, and of greater practical advantage than, those before known in the art, in the particulars of being of simpler and cheaper construction; possessing the capacity of ready replenishment whenever desired, without detachment from the driving box or manipulation of other members; and avoiding the loss of, or injury to, other parts of the driving box structure, in application, 85 operation, or renewal.

I claim as my invention and desire to secure by Letters Patent:

In a lubricant cellar, for axle boxes, the combination of a receptacle, having one end 90 open, and a hinge lug at said end, the lug having a plurality of cam faces; a lid for closing the open end of the receptacle, comprising a hinge lug, and two hinge recesses, one disposed above the other; a pintle connecting the hinge lugs; and a plate spring, 95 having an intermediate portion bearing on the inner side of the lid, a bottom portion projecting through the lower recess in the lid, and bearing on one of the cam faces of the hinge lug, and a top portion projecting 100 into the upper recess in the lid, and locking the spring in position.

JAMES G. BLUNT.
